Term of patent 14 years

Int. Cl. D12—14; D26—99

U.S. Cl. D72—1

FIG. 1 is a side elevational view of the combined automobile and reflectors showing our new design, the opposite side being a mirror image thereof.

FIG. 2 is an enlarged perspective view of one of the reflectors, the automobile and second reflector omitted for convenience of illustration.

FIG. 3 is a plan view thereof, the mounting elements being shown for illustrative purposes only.

FIG. 4 is a fragmentary sectional side elevational view thereof.

FIG. 5 is an end view of the same.

FIG. 6 is a partial view of the faceted interior surface as uniformly visible through the exterior face of the reflector.

FIG. 7 is a partial view of the faceted surface which is uniform over the interior face of the reflector.

FIG. 8 is an enlarged fragmentary cross-sectional view of the reflector lens taken on line 8—8 of FIG. 7.

The dominant features of the design are shown in solid lines.

The front and rear of the automobile are plain.

This is a continuation of application Serial No. D. 6089, filed Mar. 6, 1967.

We claim:

The ornamental design for a combined automobile and reflectors, as shown and described.
